BUCKET TRIPPER FOR STEAM SHOVELS, DREDGES, OR THE LIKE

Application filed October 11, 1929. Serial No. 399,011.

This invention relates to bucket trippers for steam shovels, dredges, or the like.

It is among the objects of the present invention to provide a novel and improved power means for opening the door of a bucket or dipper.

A further object of the present invention is to provide a fluid-operated device for actuating the tiller rope of a bucket or dipper trip lever.

A further object of the present invention is to provide a device of the character described, which is simple in construction and operation and well designed to meet the demands of economic manufacture.

Other objects of the present invention will be apparent from a consideration of the following specification taken in conjunction with the accompanying drawings, in which

Figure 1 is a side elevation of one form of the present invention mounted upon the boom of a conventional steam shovel;

Fig. 2 is a detail view of the present invention shown in section.

Referring more particularly to the drawings, it will be seen that the device is illustrated as applied to the boom 10 of a conventional steam shovel, but it will be understood that the invention is not limited to the point of application herein shown nor to the shovel herein depicted. It will readily be seen that the device may be applied in any desired position and in connection with any desired type of shovel.

The shovel herein illustrated includes in conjunction with the boom 10, the conventional dipper arm 11, bucket 12, and trip lever toggle 13, the rocking of which acts to release the door 14 of the bucket. The structure here illustrated also includes the conventional drums and cables used to operate the bucket or dipper arm and boom, the boom 10 being provided with a fluid motor 15, which is controlled by the operator for actuating the bucket arm 11, it being understood that fluid under pressure, such as steam or air from the engine, may be directed to the motor 15 for operating the same at the will of the operator.

In conventional practice, the trip lever 13 is

actuated by movement of the tiller rope 16 which passes over a pulley 17 carried by the pivoted arm 18. The rope 16 is looped about the pulley and is associated with the rear end of the dipper arm 11, as at 19. In conventional practice, the arm 18 may be manually moved by the operator through a suitable attaching cable or trip rope.

In the use of the conventional arrangement as described, the tiller rope is usually over the operator's head and the operator is usually required to stand up in order to apply sufficient energy to actuate the trip rope to open the bucket or dipper door. In so standing, the operator often loses his control of the dipper-controlling foot lever, and thus the dipper may drop and cause considerable damage while the operator is attempting to release the bucket door. In the present invention, in place of the trip rope leading to the operator, there is provided a tiller rope-operating cable 20, one end of which is associated with the arm 18 while the opposite end is carried upon a sliding frame 21 mounted in guide members 22 of the external wall of a fluid cylinder 23. The cylinder is then mounted upon the boom 10 and is provided with a piston 24 and piston rod 25 which extends from the cylinder to engage the lower end of the frame 21, as at 26.

For operating the piston, fluid is supplied to the cylinder through a pipe 27, which is connected by a valve 28 with the motor 15. The valve 28 is controlled by an operating cord 29, which leads to the operator of the shovel, the arrangement being such that when the valve is opened, fluid is admitted to the cylinder and the piston 24 is forced downwardly thus moving down the frame 21 and pulling the rope 20. With the present invention it will be seen that the strength usually required to operate the tiller rope is supplied by the fluid pressure through the pipe 27 under the control of the valve 29, whereby the operator may easily control the valve 29 to supply to the cylinder the desired amount of pressure, whereby the movement of the cylinder will move the tiller rope 20.

It will be understood that the invention

is not confined to the pivoted arm 18, and that if desired the trip rope may extend directly to the trip lever 13. It will thus be seen that the present invention is not confined to the specific structural details herein presented but that numerous changes, modifications and the full use of equivalents may be resorted to without departing from the spirit or scope of the present invention as 10 outlined in the present claims.

What is claimed is:

1. In combination with a steam shovel or the like, including a dipper, dipper arm and a boom, means for actuating the door of the 15 dipper, said means including a pulley mounted at an intermediate point on said boom, a fluid pressure cylinder mounted on said boom and rearwardly of said pulley, a piston in said cylinder and operable outwardly of the rearwardly directed end thereof, a frame enclosing said cylinder and connected at its rearwardly directed end to said piston for movement therewith, an actuating cable attached to said pulley at one end and 20 to the forwardly directed end of said frame at its other end, and means for controlling the fluid pressure supplied to said cylinder.
2. In combination with a steam shovel or the like, including a dipper, dipper arm and 25 a boom, means for actuating the door of the dipper, said means including an arm dependingly pivoted at an intermediate point on and at one side of said boom and rearwardly of said dipper arm, a pulley mounted 30 on the lower end of said depending arm, a fluid pressure cylinder mounted on the same side of said boom and rearwardly of said arm, a piston in said cylinder and operable outwardly of the rearwardly directed end 35 thereof, a frame enclosing said cylinder and connected at its rearwardly directed end to said piston for movement therewith, an actuating cable attached at one end to the dipper door operating means and to the forwardly 40 directed end of said frame at its other end, and means for controlling the fluid pressure 45 supplied to said cylinder.
